BOLSTER

William C. Hedcock, Wilmette, Ill., assignor to
American Steel Foundries, Chicago, Ill., a cor-
poration of New Jersey

Application January 23, 1931, Serial No. 510,596

11 Claims. (Cl. 195—230)

The invention relates to bolsters and particularly to cast steel truck bolsters.

In the improved form of bolster disclosed in applicant's Patent No. 1,969,131, granted August 7, 1934, the bolster structure is shown as braced and ribbed for strength and stiffness under vertical loads with the bracing continuing through the structure to greatly reinforce it for carrying eccentric loads as when concentrated on one side bearing. Although the form of bolster set out in the above patent has been found satisfactory in fulfilling the requirements for strength and stiffness, its use is somewhat limited to the form of brake mechanism employed. The present invention is therefore generally concerned with the provision of a bolster which will be independent of the brake construction used and which in addition will be primarily suited for association with a special type of brake.

Another object of the invention is to provide a cast steel bolster having improved bracing structure for reinforcing the same against collapsing tendencies and which will incorporate means adapting the same for use with a special form of brake mechanism.

Yet another object is to provide a cast steel bolster of the type described having means for adapting the same for use with special brake mechanism with provision being made for the vertical and transverse movement of the bolster relative to the brake connections.

A yet further object is to provide a bolster having the maximum depth at the center and side bearings to insure maximum strength, and which will accommodate brake connections allowing passage of the connecting rods through the bolster.

Another object is to provide a bolster incorporating truss structure principles and which will fulfill all requirements of practical manufacture and service.

With these and various other objects in view, the invention may consist of certain novel features of construction and operation, as will be more fully described and particularly pointed out in the specification, drawing and claims appended hereto.

In the drawing, which illustrates an embodiment of the device and wherein like reference characters are used to designate like parts—

Figure 1 is a side elevation, half in section, of the improved truck bolster;

Figure 2 is a top plan view of a bolster illustrated in Figure 1;

Figure 3 is a sectional view of one end of the

bolster taken substantially on the plane indicated by line 3—3 of Figure 1; and

Figure 4 is a sectional view through the center of the bolster.

The improved structure consists essentially in a hollow box girder having a center plate or bearing 10 defined by a circular rim 12 upon which the weight of the car body is normally carried, in combination with side bearings 14 and spring seats 16. The top wall of the bolster comprises the center plate 10 or bearing, the portions 18 between the center plate and the side bearings, the side bearings 14, and the extensions 20 toward the ends of the bolster which serve as the compression member. The bottom wall 15 of the bolster serves as the tension member and comprises the substantially straight and horizontal central portion 22 extending beneath the central box strut structure 24 and continuing in the substantially straight diagonal portions 26, which merge with the spring seats 16. The strut 24 is located beneath the center plate extending between positions substantially beneath the rim 12 and continuing from the top wall to the bottom wall of the bolster. Integrally joining the web members 30 of the strut and positioned substantially centrally of the same are portions 32 forming a seat for supporting the center pin in alignment with the aperture 34 in the center plate.

Beneath each side bearing 14 and extending from the top wall to the bottom wall of the bolster is provided a substantially semi-circular side bearing strut 38, the strut being provided with flanges 40 joining the same with the bottom wall 26 and connecting with the upwardly sloping braces or webs 36 adjacent the upper ends of said struts. Said braces extend longitudinally of the bolster and merge with the compression member 18 at a point adjacent the central strut 24. The ends of the bolster are provided with vertical ribs 42 extending from points under the side bearing 14 as at 44 to the end of the extensions 20 vertically downward, joining with the wall comprising the spring seats 16.

The bolster has the top and bottom walls spaced and connected on each side with substantially vertical side walls 46 which merge into end side walls 50 forming the usual column guide faces and being provided with column guide flanges 52, and the upper chord may be provided with the lightening holes 54 disposed between the side bearings 14 and the ends of the bolster, and likewise the bottom chord 26 intermediate the 56

struts 38 and the center post may be provided at the lightening holes 60.

A feature of the present invention resides in the provision of a bolster which will incorporate means adapting the same for use with special brake mechanism, whereby the connecting rods of the brake mechanism can be centrally located in a plane passing through the bolster. For this purpose the side walls 46 are provided with a plurality of spaced openings 54, located an equal distance from the center line of the bolster and within the portion of the side walls defined by the strut 24. Both side walls 46 are provided with similar openings in alignment with each other, and for forming an unobstructed passage through the bolster, the longitudinally extending web members 30 of the center plate strut are likewise provided with similar openings 56 located an equal distance from the center line of the bolster and in alignment with openings 54. The disposition of the openings forms a center post having a plurality of spaced pillars, one of which is on the transverse center line of the bolster whereby adequate strength is provided even though a large amount of metal is removed by providing the openings. Additional openings for accommodating the pull rods of the brake mechanism are provided and include the openings 58 located in the side walls 46 at an equal distance from the central line of the bolster and disposed wholly below the bottom edge of the braces 36. Said openings are preferably between the struts 38 and the lightening holes 61 which holes are disposed between the center bearing 10 and the side bearings 14, the braces 36 forming depending reinforcements for the upper chord adjacent said lightening holes. In use it is only necessary to provide the bolster with one opening 54 and one opening 58, but for the purpose of symmetry and to make the bolster right and left, the openings are provided on both sides of the center line as shown.

An important feature of this bolster is the construction of the broad center plate strut whereby it embraces the openings for passage of the brake rods. The broad strut 24 provides a firm support for the center plate, and, by distributing the center plate load over an extended area on the tension member, embracing the brake rod openings 56, the tension member is so supported and reinforced that its strength is not impaired by the presence of the openings 54 in the side walls. Also the tension member 22, following a substantially straight line between the bases of the strut 24, is subjected principally to direct tension stresses and the bending stresses therein are reduced which also compensates for the presence of the openings 54. Furthermore the webs 30 about the interior openings 56 provide a further reinforcement for the structure adjacent the brake rod openings.

It is to be understood that I do not wish to be limited by the exact embodiment of the device shown, which is merely by way of illustration and not limitation, as various and other forms of the device will of course be apparent to those skilled in the art without departing from the spirit of the invention or the scope of the claims.

I claim:

1. In a bolster, the combination of top and bottom chords and connecting side walls forming substantially a box section, a center bearing on the upper of said chords, a center post connecting said chords, side bearings on the upper of said chords spaced from said center bearing, lightening holes in said upper chord intermediate the

center and side bearings, struts adjacent said side bearings and connecting said chords, aligned apertures in the spaced side walls intermediate the upper and lower chords and between said lightening holes and said struts, said struts each having a brace extending longitudinally of said bolster and depending from said upper chord, the lower edge of each of said braces merging into its respective strut adjacent the top thereof and disposed wholly above said apertures whereby said apertures are adapted to permit the unrestricted passage of brake rigging through the bolster. 5

2. In a bolster, the combination of a body portion having upper and lower chords and connecting side walls forming substantially a box section, 15 a center bearing on one of said chords, a center post connecting said chords and having an opening therein, said center post being of substantially greater width than said center bearing for compensating for the reduction in metal due to the provision of said opening in said post, and said side walls each having an opening aligned with said first named opening for permitting the unrestricted passage of brake mechanism through said bolster. 20

3. In a bolster, the combination of a body portion having upper and lower chords and connecting side walls forming substantially a box section, center and side bearings on one of said chords, a center post connecting said chords and having an 30 opening therein, said center post being of substantially greater width than said center bearing for compensating for the reduction in metal due to the provision of said opening in said post, said opening being adapted to permit the passage of 35 brake mechanism therethrough, said side walls having aligned openings therein adjacent said side bearings and spaced from said center post for permitting the unrestricted passage of brake mechanism through said openings. 40

4. In a bolster, the combination of a body portion having upper and lower chords and connecting side walls forming substantially a box section, one of said chords having center and side bearings, means connecting said chords including 45 a center post of substantially greater width than said center bearing, said center post having openings therein disposed on each side of the transverse center line of said bolster, whereby a plurality of supporting pillars are provided, one of 50 said pillars being on said transverse center line, said side walls having openings therein aligned with the openings in said center post for permitting the unrestricted passage of brake mechanism through said bolster. 55

5. In a bolster, the combination of a body portion having upper and lower chords, one of said chords having center and side bearings, means connecting said chords including a center post of substantially greater width than said center bearing, said center post having openings therein for permitting the unrestricted passage of brake mechanism through said bolster, said openings being disposed on each side of the transverse center line of said bolster, whereby a plurality of 65 supporting pillars are provided, one of said pillars being on said transverse center line. 60

6. In a bolster, the combination of a body portion having upper and lower chords, and connecting side walls forming substantially a box 70 section, center and side bearings on one of said chords, a center post connecting said chords and having an opening therein, said center post being of substantially greater width than said center bearing for compensating for the reduction 75

in metal due to the provision of said opening in said post, and said side walls each having an opening aligned with said first named opening, said side walls having aligned openings 5 therein adjacent said side bearings and spaced from said center post, each of said openings permitting the unrestricted passage of brake mechanism through said bolster.

7. In a bolster, the combination of a body portion having upper and lower chords, and connecting side walls forming substantially a box section, center and side bearings on one of said chords, a center post connecting said chords and having an opening therein, said center post being of substantially greater width than said center bearing for compensating for the reduction in metal due to the provision of said opening in said post, and said side walls each having an opening aligned with said first named opening, said side walls having aligned openings 15 therein adjacent said side bearings and spaced from said center post, each of said openings permitting the unrestricted passage of brake mechanism through said bolster, and strut connecting said upper and lower chords adjacent said side bearings.

8. In a bolster, the combination of a body portion having upper and lower chords, and connecting side walls forming substantially a box section, center and side bearings on one of said chords, a center post connecting said chords and having an opening therein, said center post being of substantially greater width than said center bearing for compensating for the reduction in 20 metal due to the provision of said opening in said post, and said side walls each having an opening aligned with said first named opening, said side walls having aligned openings therein adjacent said side bearings and spaced from said center 25 post, each of said openings permitting the unrestricted passage of brake mechanism through said bolster, and struts connecting said upper and lower chords adjacent said side bearings, and merging into one of said chords adjacent said center bearing, said struts being disposed to substantially clear said openings.

9. In a bolster, the combination of a body portion having upper and lower chords and connecting side walls forming substantially a box section, 30 a center bearing on one of said chords, a center post connecting said chords, said center post including spaced vertical webs connected by struts adjacent the ends thereof, said webs and said

side walls each having an opening, said openings being aligned for permitting the unrestricted passage of brake mechanism through said bolster, the length of said center post adjacent the opening therein being substantially longer than the 5 diameter of the center bearing to compensate for the reduction of metal due to the provision of the opening in each of said webs.

10. In a bolster, the combination of a body portion having upper and lower chords and connecting side walls forming substantially a box section, one of said chords having center and side bearings, means connecting said chords including a center post, said center post including spaced vertical webs connected by struts adjacent the ends thereof, said webs and said side walls each having spaced openings, said openings being aligned and disposed on each side of the transverse center line of said bolster for permitting the unrestricted passage of brake mechanism through said bolster, the length of said center post adjacent the openings therein being substantially longer than the diameter of the center bearing to compensate for the reduction of metal due to the provision of the openings in each of 25 said webs.

11. In a bolster, the combination of top and bottom chords and connecting side walls forming substantially a box section, a center bearing on the upper of said chords, a center post connecting said chords, side bearings on the upper of said chords spaced from said center bearing, lightening holes in said upper chord intermediate the center and side bearings, struts adjacent said side bearings and connecting said chords, aligned 35 apertures in the spaced side walls intermediate the upper and lower chords and between said lightening holes and said struts, said struts each having a brace extending longitudinally of said bolster and depending from said upper chord 40 and forming reenforcing means for said lightening hole, the lower edge of each of said braces merging into its respective strut adjacent the top thereof and disposed wholly above said apertures, aligned apertures in said side walls adjacent said center bearing and disposed intermediate the top and bottom chords of said bolster and wholly below said lower edge of said brace, whereby certain of said aligned apertures may selectively permit the unrestricted passage of 45 50 brake rigging through the bolster.

WILLIAM C. HEDGCOCK.

CERTIFICATE OF CORRECTION.

Patent No. 2,029,822.

February 4, 1936.

WILLIAM C. HEDGCOCK.

It is hereby certified that error appears in the printed specification of the above numbered patent requiring correction as follows: Page 1, second column, line 53, for the numeral "61" read 160; and that the said Letters Patent should be read with this correction therein that the same may conform to the record of the case in the Patent Office.

Signed and sealed this 17th day of March, A. D. 1936.

Leslie Frazer
